UNITED STATES PATENT OFFICE

2,642,788

TUNNEL PORTAL CONSTRUCTION

William Earle Andrews, New York, N. Y.

Application April 21, 1948, Serial No. 22,417

2 Claims. (Cl. 94—1)

1

This invention relates to a tunnel construction; more particularly to a portal approach for tunnels; and still more particularly to the illuminating features of the approach to a tunnel portal.

It is an object of my invention to minimize the human hazard involved in accommodation of the eyes in the transition in passing from a high level of illumination to a point having a low level of illumination, such as is involved in entering the portal of a tunnel during daylight, to the low level illumination of the tunnel furnished by artificial illumination. My invention is concerned with the provision of a portal construction for tunnels joining roadways or railway right-of-ways and which are entered by vehicles at relatively high speeds from a point having a high level of illumination to the interior having a relatively low level of illumination.

It is contemplated by my invention to provide a portal construction which includes a canopy for the approach, shielding light to adjust the intensity of light on the roadway or approach adjacent the tunnel portal to effect a transition of light values gradually, with some relationship to the ability of the human eye to accommodate itself to the transition from the illumination of the roadway under high intensity values to low intensity values, and thereby reduce the hazard involved in effecting a transition from the high level value to the low level values abruptly or within a time factor which would involve a lag in eye accommodation, with its consequent hazard.

Still more particularly, it is an object of my invention to provide a canopy construction for the entrance portal of tunnels to shield the roadway from illumination gradually, so that the eye may accommodate itself in passing into the tunnel with its relatively low level illumination factors, without hazard by reason of momentary loss of visibility.

To attain these objects and such further objects as may appear herein, or be hereinafter pointed out, I make reference to the accompanying drawing forming a part hereof, in which—

Figure 1 is a plan view of a roadway construction including tunnel approaches and portals illustrating my invention;

Figure 2 is a magnified section taken on the line 2—2 of Figure 1;

Figure 3 is a plan view of a canopy at a portal;

Figure 4 is a side elevation taken on the line 4—4 of Figure 3;

Figure 5 is a section taken on the line 5—5 of Figure 3;

Figure 6 is a fragmentary plan view of the portal construction and canopy, with illustration of supplementary illumination;

Figure 7 is a diagrammatic chart illustrating the relationship of light values to distance

2

traversed in a canopy to a tunnel portal in accordance with my invention;

Figure 8 is a perspective view of the tunnel portal and adjacent area to provide visually the representation of the coordinate factors of the chart;

Figure 9 is a diagram chart illustrating the relationship of light values to distance traversed in a portal construction in accordance with existing tunnel portals and adjacent areas;

Figure 10 is a perspective view of the portal and adjacent area to provide visually the representation of the coordinate factors of the chart.

Making reference to the drawing, there is illustrated a roadway construction wherein a tunnel 10 is intended to join roadways 11 and 12 to have the respective portals 13 and 14 thereof adjacent an area subject to ordinary daylight illumination. In accordance with the exemplification, the portals 13 and 14 include entrance ramps 15 and 16 and exit ramps 17 and 18, descending from the level of the roadways 11 and 12. Each of the portals 13 and 14 has side walls 19, 20, and 21, 22, respectively, with division walls 23 and 24, respectively, separating the roadways 15, 17 and 16, 18, at the portals 13 and 14. Coping 25, 26, 27, 28 overlies the wall structure extending above the roadways above the portals.

Each of the entrance roadways 15 and 16 is provided with a canopy 29 and 30, respectively, comprising angularly edged segments 31 and 32 overhanging the roadway from the crotch 33 to the points of the branches 34, 35, which merge into the walls 19 and 23, respectively, providing between the segments 31 and 32 a skylight 36 which graduates in outline from points 34, 35 to the crotch 33, previously described.

The adjacent entrance portal area constituting the walls 19, 23, the segments 31 and 32, have facing 37 of material with due regard to its light reflectance value as well as to the structural requirements in the tunnel zone. The ceiling of the segments 31 and 32 may likewise be finished with facing material 38, such as tile, to augment or qualify the light reflectance value of the adjacent area, whether by daylight illumination or augmented by artificial illumination, as will appear more clearly hereafter.

The extensiveness of the ramp and the canopied section adjacent the entrance portal to secure the reduction in hazard as contemplated by me is a factor of width of roadway, allowable speed of traffic, height of the vertical walls to the ramp, as well as adjacent terrain. In general, however, I have found that with a roadway of approximately twenty nine feet, with a canopy which graduates from full opening to the crotch in about one hundred sixty feet, that an apron of about forty feet to the portal opening exemplifies a type of graduation of illumination which makes the transition from the high level of

illumination experienced in daylight to the illumination by artificial light within the tunnel to accommodate the eye to the transition, without loss of visual efficiency, and permitting un-retarded movement of traffic from the high level light intensity to the low level light intensity.

It is contemplated by a more particular phase of my invention also to supplement the illumination adjacent the portal with artificial sources of light. In Figure 6 I have illustrated a fragmentary portion of the portal including the canopy wherein a series of light sources L beginning from beneath the canopy segments 31 and 32 and to and within the tunnel 10 are strung along at varying distances from each other, being more sparsely located at and adjacent the crotch, more concentrated from this point to adjacent the tunnel as the portal aperture is entered, and then uniformly spaced within the tunnel zone.

In Figures 7 to 10 I have graphically illustrated the relative value of a tunnel portal constructed in accordance with my invention as compared with existing installations known to me, plotting average foot candles against distance, in which the ordinate axis is plotted in foot candles and the abscissa in distance corresponding to feet.

Figure 8 schematically superimposed the entrance roadway covered by the canopy in accordance with my invention up to the portal and a short distance from the portal into the tunnel. In the chart there is plotted foot candles experienced from the extreme condition, i. e. average daylight for the longest day of the year, June 21st, curve I; and for the shortest day of the year, December 21st, curve II; and the yearly average daylight, curve III. The curves taper to the constant which may be maintained within the tunnel 10 of approximately 5 foot candles, as may be maintained by the artificial light uniformly maintained in the tunnel itself. A segment IIIa diverts from the curve III to the extent that extra artificial light is added adjacent the portal in accordance with the embodiment illustrated in Figure 6 and as above noted may be effected in varying concentrations.

In general, it will be observed that the light values in foot candles of measurement graduate from the daylight intensity to the low level intensity of the tunnel of 5 foot candles within the distance of about two hundred and fifty feet without any abrupt change.

In Figures 9 and 10 there is plotted a relationship of light in foot candles in the ordinate under conditions employing nothing more than the graduated wall from the roadway level adjacent the ramp to the portal. Curve IV plots the change for average daylight for the longest day of the year; curve V shows the light values against distance for average daylight for the shortest day of the year; curve VI shows the light values plotted against distance for the yearly average daylight. Segment VIa of curve VI departs from the normal curve VI where the portal illumination is augmented by additional artificial light of approximately 75 foot candles.

It will be apparent from a comparison of the charts that the transition from maximum illumination to minimum illumination in the case of the construction illustrated in Figure 10 is of the order of from ten to thirty feet whereas in accordance with the construction shown in Figure 8, the graduation of light under the canopies is accomplished in a distance of almost one

hundred seventy five feet. The eye therefore has more than four times the time element to accommodate itself to the transition in light intensity.

It will be observed that while in the construction which I have provided and which includes at the approach to the portal, a down grade ramp partially shielded by the walls which are provided by combining with a roadway of approximately thirty feet in width, canopy segments which converge within a distance of approximately one hundred sixty feet from the apex to the crotch, it will be understood that where the tunnel portal is on a level with the approach or is reached by an ascent in the approach, the support for the canopy and the convergence of the canopy segments may require modification, in accordance with the existing terrain.

While I may, by my construction, as above stated, augment the natural daylight illumination adjacent the portal, the uniform graduation in light intensity in accordance with my construction requires the use of fewer extra fixtures at the portals than would be involved if compensation for lack of fast accommodation of the eyes is endeavored to be made at a point inwardly spaced from the portal, thereby effecting very substantial installation economies.

Under the construction in accordance with my invention, traffic may proceed at unretarded speeds without hazard as there is no requirement to reduce speed in approaching the artificial illumination of the low magnitude maintained within the tunnel after passing the portal.

Having thus described my invention and illustrated its use, what I claim as new and desire to secure by Letters Patent, is:

1. An entrance roadway leading to a tunnel 40 portal comprising supports along said roadway leading to said portal, a canopy partially overlying said entrance roadway and tapering from the sides of said supports at a distance of approximately two hundred feet to a point over said roadway approximately forty feet from said portal, to form a V-shaped notch in said canopy exposed to daylight, to reduce natural illumination whereby in approaching and entering said portal at the rate of movement ranging approximately from fifteen to sixty six feet per second, over said distance hazards involved in lag in human eye accommodation are overcome.

2. An entrance roadway leading to a tunnel 55 portal comprising side walls leading to said portal, a canopy partially overlying said roadway and tapering from each of said side walls at a distance of approximately two hundred feet to a point over said roadway approximately forty feet from said portal to form a V-shaped notch in said canopy exposed to daylight to reduce natural illumination whereby, in approaching and entering said portal at a rate of movement ranging approximately from fifteen to sixty six feet per second over said distance, hazards in lag in the human eye accommodation are overcome.

W. EARLE ANDREWS.
